WORKER'S THREAD KIT

Minnie Federman Corder, New York, N. Y.

Application November 26, 1941, Serial No. 420,473

4 Claims. (Cl. 223—106)

This invention relates to a worker's kit for thread, yarn, or the like, and of a character that will enable a worker to have available for instant use, a large variety of different colored threads or yarns of desired length.

While the invention is susceptible of many uses, it has particular application in the clothing trade in which some of the workers, as for instance the button-hole makers, are called upon, in the course of the day's work, to use a large number of threads of different colors. It is essential that these threads be instantly available if time and effort are not to be wasted.

In making buttonholes for clothing, it is the custom to edge the hole that has been cut in the cloth with a heavy thread known as gimp, by binding the gimp along the edge of the hole with silk thread known as buttonhole twist. The gimp comes on spools ready for use whereas the silk, although likewise on spools, must be waxed before using in order to preserve it against unravelling.

During the course of a day, a worker in the trade might be called upon to use silk thread in a large variety of colors and since she is also responsible for waxing the thread, it is the practice first to wax it, then cut it to length and bind the lengths together at the center. The hank, thus made, is folded upon itself and pushed up through a hole in the cover of a box with the free ends dangling down into its interior. The same procedure is followed with the silk thread of other colors so that when the worker has her kit ready for use, it will contain perhaps seventy-five to one hundred hanks of silk thread, all of different colors, and which have a loop projecting up beyond the cover of the box so that the worker can select individual threads of the desired shades as required.

The boxes heretofore used for the kits were made of ordinary cardboard in order to exert sufficient friction upon the hanks to hold them in position in their holes, at least, when the hanks are initially inserted therethrough.

However, as the worker continues to select threads from the hanks, they decrease in size and this, together with the fact that the holes in the box top wear, the frictional holding effect diminishes with the result that long before the last threads in the hanks have been used, they fall down into the box and become hopelessly entangled with the threads of other hanks which have suffered the same fate. Rather than trouble themselves to salvage the tangled threads, the workers discard it.

It has been conservatively estimated that in the

average plant where work of this character is done, the practice results in a substantial loss from material alone, not to mention the loss of time it takes to wax the discarded thread.

According to the present improvements, there is provided a kit which will eliminate these losses entirely and which because of its construction and durability will result in other savings as well.

Referring to the drawing:

Fig. 1 is a perspective view of an improved kit and with a cover in place which has been partially broken away to expose the kit beneath;

Fig. 2 is a vertical longitudinal sectional view on line 2—2 of Fig. 3;

Fig. 3 is a plan view of the kit shown in Fig. 1, with the cover removed, a part of the lid of the kit being broken away to show the underlying compartment;

Fig. 4 is an enlarged fragmentary vertical sectional view through an end portion of the improved kit near the top; and

Fig. 5 is an enlarged fragmentary vertical sectional view through an end portion of the improved kit near the bottom.

The improved kit is in the form of a box having a bottom 10, back, front and end walls 11, 12 and 13, and a cover 14 which is hinged to the back wall at the top. For reasons detailed later on, the box is formed with three compartments 15, 16 and 17 defined by walls 18 and 19 extending from front to rear, the central compartment being substantially smaller than the two end compartments which preferably are the same size.

The box is formed of a durable material such as wood, and the cover 14, above the two end compartments 16 and 17, is drilled with a plurality of holes 20 to accommodate hanks 21 of thread of different varieties.

The hanks of thread 21 are prepared in the usual manner, i. e., the thread is waxed, cut to proper length and the lengths bound together at the center by a loop of cord 22. Then the hanks, at their folded centers, are pushed upwardly through the holes 20 but, instead of relying upon friction to hold them in place, the ends of the loops are tied to screw eyes 23, threaded into the cover and located one adjacent each of the holes 20. Since the hanks are thus positively secured in place, it is an impossibility for them to fall down into the box and become entangled one with another. The result is that the worker can use every thread in the hank. It will be understood, of course, that when the kit is in use the top 14 will be closed down and preferably secured by a latch 24 and that the worker will select a

thread of the desired color merely by picking it from the hank with the fingers and pulling it up through the hole 20 and through the loop 22.

In addition to the advantages inherent in positively holding the hanks against falling down into the box interior, the elimination of the requirement of friction permits the kit to be made of a rigid and consequently durable material having long life and permits also the use of holes 20 of substantial diameter so that the hanks can be made of a greater number of threads than would otherwise be the case. In other words, the worker will be able to use the kit for a longer period without reloading. Indeed, the only limitation upon the size of the holes 20, and consequently the size of the hanks 21 accommodated by them, is the total size of the box which must be reasonable for the worker's use and the number of different color or character hanks the worker must have available. Another advantage flows from the fact that should the hanks tend to work up out of the holes, the worker can open the lid and pull them down since, of course, they are anchored to the eyes 23. This will prevent the thread loops above the lid from becoming confused with threads of different hanks so that the worker will not inadvertently select one thread where the intention is to select another.

Provision is also made in the kit for the gimp so that it will always be convenient to the worker. Formerly, the spools of gimp were left loose on the work bench for the worker to cut off the desired lengths as needed. Frequently the spools were mislaid, dropped on the floor or have some other mischance befall them, resulting in much inconvenience and loss of time. The central compartment 15 in the present kit provides a handy and relatively permanent location for the gimp. It accommodates two spools of gimp 25 and these are provided with a mandrel 26, the ends of which project beyond the spool faces and are received in vertical slots 27 formed in the opposed walls 18 and 19 of the central compartment (Figs. 2 and 3). The slots terminate in shoulders at their lower ends to furnish bearings for the mandrel at a level which will permit the spools freely to rotate as the gimp ends are pulled. The free end of the gimp from the front spool passes out through a hole 28 in the adjacent front wall 12 of the kit while that of the rear spool passes out through a hole 29 in the adjacent rear wall. The worker pulls the gimp through the hole until the required amount can be cut off.

In order to prevent access to the kit by those other than the worker, particularly in the worker's absence, the kit is fastened to the bench at the worker's position by screws 30 located one at each corner of the kit and which pass through holes in the bottom and are threaded into the underlying bench. A cover 31 consisting of top, front, rear and end walls, is placed over the kit and is secured to the bench by hasps 32 fastened to the end walls of the cover and which are slotted to cooperate with staples 33 which are fastened to the bench. A small padlock 34 serves to lock the cover in place. For convenience, the cover is provided at the top with a handle 35 to facilitate its removal and replacement.

In the accompanying drawing, the invention has been shown merely in preferred form and by way of example, but obviously many variations and modifications may be made therein which will still be comprised within its spirit. For instance, a snap ring of metal could be used as the

binding means for the hanks and the ring in turn fastened by some suitable device to the eyes. It is to be understood, therefore, that the invention is not limited to any specific form or embodiment, except insofar as such limitations are specified in the appended claims.

Having thus described my invention, what I claim is:

1. A worker's thread kit comprising a rigid member forming one wall of a compartment and provided with a plurality of holes to accommodate a corresponding plurality of thread hanks, the individual threads of which are adapted to be doubled upon themselves and the doubled ends extended through the corresponding holes so as to present a loop, means for binding the individual threads of each hank together at the loop, and a screw eye associated with each of said holes and threaded into said member in its outer surface to provide an anchorage for the binding means outside the compartment whereby the hanks, as well as the individual threads thereof are prevented from dropping through the holes into the compartment.

2. A worker's thread kit comprising an apertured member provided with at least one aperture of a size to loosely accommodate the several strands of thread hanks, the individual threads of which are doubled upon themselves, and the looped ends of which are extended through the aperture and beyond the surface of said member, anchor means disposed angularly with respect to a surface of said member adjacent the aperture thereof, a separate binding member looped through the projecting looped end of said hank and secured to said anchor means for supporting said hank from its looped end loosely in said aperture and preventing displacement of said projecting looped end of said hank from said member.

3. A worker's thread kit comprising a rigid member provided with a plurality of apertures, each of a size to loosely accommodate the several strands of thread hanks, the individual threads of which are doubled upon themselves and the looped ends of which are extended through the aperture and beyond the surface of said member, anchor means extending from one surface of said member in a direction substantially at right angles thereto and having a looped part passable through the looped end of said hank providing means for supporting said hank from its looped end loosely in said aperture and preventing displacement of said projecting looped end of said hank from said member.

4. A worker's thread kit comprising a rigid member forming one wall of a compartment and provided with a plurality of apertures, each of said apertures being of a size to loosely accommodate the several strands of thread hanks, the individual threads of which are doubled upon themselves, and the looped ends of which are extended through the aperture and beyond the surface of said member, and means extending from the outer surface of said member and located adjacent to said apertures providing an anchor for a flexible member, and a flexible member attached to said anchor means and passed through the projecting looped end of said hank for supporting said hank from its looped end loosely in one of said apertures.

MINNIE FEDERMAN CORDER.
